SOUND REPRODUCING SYSTEM AND COIN
COLLECTING ACTUATOR THEREFOR

William S. Farrell, Los Angeles, Calif.

Application January 13, 1941, Serial No. 374,192

5 Claims. (Cl. 194—9)

My invention relates to a coin actuated device and has particular reference to a new sound reproducing system and a coin collecting actuator therefor.

Numerous attempts have been made in the past in connection with various types of coin controlled mechanisms to provide for the insertion of two or more coins at one time in such manner that the mechanism will be operated the same number of times as there were coins inserted in the device. The prior devices intended to provide this type of operation are characterized by great complexity in the number of parts and mechanisms employed, most of these devices including some form of counting element adapted to register each coin as it is inserted into the device and adapted to cooperate with a periodically actuated re-setting mechanism adapted to reduce the registered quantity of coins by one each time the coin controlled mechanism was actuated to an extent represented by the value of one of the coins.

There has recently developed a need for a new type of coin collecting actuator which is capable of receiving at one time two or more coins. This need has become particularly acute where it is desired to employ a considerable number of such coin collecting devices with a single mechanism controlled thereby. For example, in restaurants, cocktail lounges, and like places, it is oftentimes desirable to provide a coin controlled phonograph or other sound reproducing device and to incorporate therewith a considerable number of coin collecting mechanisms disposed at different strategic locations throughout the establishment. The complexities above referred to are obviously multiplied by the number of coin collecting devices employed, with the result that the cost of manufacture, installation, and maintenance rises to a prohibitive value.

Another disadvantage is encountered when a single sound reproducing device or phonograph is adapted to be controlled from any one of a number of coin collecting stations. This difficulty resides in the fact that the musical selection reproduced by such a device can be heard by all of the persons within the establishment so that all of such persons obtain jointly the benefit which is derived from the coin inserted in a coin collecting device by a single one of such persons.

The present invention is directed to a coin collecting device which is capable of receiving two or more coins at one time and which is so constructed as to avoid the above noted disadvantages as regards complexity of construction

and cost of manufacture. This invention is also directed to the provision of a novel sound reproducing system for use with a plurality of such coin collecting devices, and of such type that the sound reproduction in response to the insertion of a coin in one or more of the coin collecting stations is limited to such of the stations as have collected coins.

In view of the large number of restaurants, cocktail parlors, bowling alleys, and like places which are now equipped with loud speaking, sound reproducing devices of conventional character, it is highly desirable that a sound reproducing system of the character outlined in the preceding paragraph be so arranged as to permit it to be connected to and employed with such conventional coin operated phonographs. Furthermore, the system should be such as to permit the conventional phonograph to be adapted for use therewith with a minimum amount of revision and changes, and the system should furthermore be so constituted and arranged as to permit the addition of additional coin collecting stations to the system or the removal from the system of unwanted coin collecting stations without requiring any revision or alteration of that portion of the system which is not to be changed.

It is therefore an object of my invention to provide a sound reproducing system employing a plurality of coin collecting stations, each of which is provided with a sound producing means adapted to be rendered operative upon the collection of a coin to reproduce sounds originating at a central reproducing station.

It is also an object of my invention to provide a sound reproducing system of the character set forth in the preceding paragraph in which means is provided for insuring that a particular sound producing means will be maintained operative a length of time at least as great as that represented by the value of a coin inserted to render such sound reproducing device operative.

It is a still further object of my invention to provide a sound system of the character set forth hereinbefore in which a means is provided for suspending the actual collection of a coin deposited in a coin collecting station until the commencement of the period of sound reproduction for which the coin was inserted.

It is additionally an object of my invention to provide a sound system of the character set forth in the preceding paragraphs in which the coin collecting means is operable to receive and hold a plurality of coins without collecting the same,

the device functioning to periodically collect one of such coins at the beginning of each of a plurality of time periods of sound reproduction.

It is also an object of my invention to provide a sound system of the character set forth in the preceding paragraphs in which the insertion of a coin in one station does not affect the operation or non-operation of other stations.

It is a still further object of my invention to provide a sound system of the character set forth hereinbefore which is so arranged as to permit the adding to or removal from the system of one or more coin collecting stations without requiring the alteration of that portion of the system associated with others of such stations.

It is additionally an object of my invention to provide sound producing and coin collecting apparatus which is so constructed and arranged as to permit its ready connection to sound reproducing devices of known types to thereby provide a sound reproducing system of the character set forth in the preceding paragraphs.

It is also an object of my invention to provide coin collecting devices which are capable of cooperating with each other upon the insertion of one or more coins to actuate a coin controlled mechanism in such manner as to deliver to each person depositing coins full value for each of such coins.

Other objects and advantages of my invention will be apparent from a study of the following specification, read in connection with the accompanying drawings, wherein:

Fig. 1 is an elevational view illustrating a typical installation of the sound reproducing system of my invention;

Fig. 2 is an elevational view illustrating the details of construction of one form of coin collecting station which may be employed with the system of my invention, Fig. 2 illustrating the appearance of the device as viewed from the rear with the rear cover removed;

Fig. 3 is a view similar to Fig. 2 but illustrating the instrumentalities which are mounted on the inside surface of the rear cover of the coin collecting station;

Fig. 4 is a fragmentary longitudinal sectional view taken substantially along the line IV—IV of Fig. 3 and illustrating one of the operative positions of the coin collecting mechanism;

Fig. 5 is a view similar to Fig. 4 but illustrating another operative position of the coin collecting mechanism;

Fig. 6 is likewise a sectional view similar to Figs. 4 and 5 but illustrating still another operative position of the coin collecting mechanism;

Fig. 7 is an elevational view illustrating the general arrangement of parts and mechanisms employed in an impulse relay of my invention;

Fig. 8 is a schematic wiring diagram illustrating the various electrical connections employed in one form of sound reproducing system constructed in accordance with my invention.

Referring to the drawings, I have illustrated in Fig. 1 a typical installation of the preferred form of sound reproducing system of my invention as including a plurality of coin collecting stations 1, 2, 3 and 4. While Fig. 1 illustrates the employment of four of such coin collecting stations, it is to be understood that the system may include more or less of such stations, as desired. Each of the stations 1, 2, 3 and 4 is illustrated as being mounted on a bar or counter

5 and being spaced therealong from each other at any desired interval.

Each of the stations 1-4 are interconnected by means of a multiple conductor electric cable 5 and also by such cable 6 to an adapter unit 7 which is preferably attached to or closely associated with a conventional form of coin actuated phonograph 8. The adapter unit 7 is preferably connected as by means of an electric cable 9 to the electrical mechanisms embodied in the phonograph 8 in a manner to be more fully explained hereinafter. The adapter unit 7 and the phonograph 8 may each receive power for their operation as by means of conventional electrical connections 10a and 10b to a suitable source of electric current 11.

Each of the coin collecting stations 1-4 is preferably constructed along the lines illustrated in Figs. 2 and 3 and each preferably includes a back cover plate 12 to which is secured a pair of strip members 13 and 14 defining a coin chute 15. The back cover 12 is adapted to be secured to the back of a front housing member 16 in such position that the coin chute 15 will register with a coin receiving aperture 17 formed in the housing 16. The housing 16 is preferably provided with a sizable aperture 18 behind which is positioned a loud speaker 19 or other equivalent sound producing means. The lower portion of the housing member 16 is preferably lined with felt 20 or other similar padding material for the purpose of deadening the sound of coins which are dropped to the bottom of the housing 16 by their passage through the coin chute 15. If desired, certain portions of the housing 16 may be formed of transparent or translucent material 21 for the purpose of ornamentation, these translucent portions being lighted from the interior as by means of electric lamps 22 mounted upon suitable brackets 23 which are in turn secured to the rear cover plate 12.

The rear cover plate 12 also serves to support a pair of coin switches CS-1 and CS-2, the operating arms 24 of which are disposed in a position to be engaged by coins passing down the coin chute 15. Each of the switches CS-1 and CS-2 include electrical contacts 26 adapted to be closed to complete an electric circuit by the engagement of a coin with the operating arms 24.

50 The coin switches CS-1 and CS-2 are adapted to cooperate in a manner to be hereinafter described with a coin relay CR which is also mounted upon the rear supporting plate 12 and which is also adapted upon energization to close certain electrical contacts associated therewith and at the same time to actuate a coin feeding mechanism 27 or escapement for controlling the passage of a coin along the coin chute 15 (see Fig. 4). The coin relay CR accordingly includes an armature 28 which in turn carries an extension member 29 mutually engaged with an upper escapement member 30 and a lower escapement member 31. The escapement member 30 includes an upper coin engaging projection 32 and a lower coin engaging projection 33 each disposed in the coin chute 15.

The escapement member 30 is preferably pivoted as indicated at 34 in such manner that one or the other but not both of the projections 32 or 33 may occupy a position such as to engage a coin 35 which is received in the coin chute 15. The lower escapement member 31 also includes a coin engaging projection 36 and the member 31 is pivoted as indicated at 37 in such manner as to be moved from a position disposing the pro-

jection 36 in a position to engage a coin to a position sufficiently removed from the coin chute 15 as to permit a coin to pass thereunder.

The escapement members 30 and 31 are so coordinated that the coin engaging projections 32 and 36 are simultaneously disposed in positions to engage coins in the coin chute 15 at a time when the coin engaging projection 33 is removed from the coin chute. Furthermore, the projections 32 and 36 are each disposed in such location relative to the coin switches CS-1 and CS-2, respectively, as to cause the electrical contacts 28 associated with each of these switches to be closed at a time when a coin is engaged by each of these coin engaging projections.

The manner in which the above described instrumentalities function to control the coin actuated phonograph 8 may be understood by having reference to the wiring diagram comprising Fig. 8. In this figure each of the dashed lines 1, 2, 3 and 4 indicate the coin collecting stations 1-4 and the various instrumentalities illustrated diagrammatically in this figure and enclosed by these dashed lines represent the instrumentalities enclosed within each of the coin collecting stations. Similarly, the dashed line 7 encloses the various instrumentalities comprising the adapter unit 7 and the dashed line 8 represents the coin actuated phonograph 8.

In this connection the coin actuated phonograph 8 is preferably of a conventional well-known type employing an electrical sound reproducer 38 coacting with a vacuum tube amplifier 39 adapted in turn to coact with a sound reproducer or loud speaker 40. The phonograph 8 preferably also includes a record changing mechanism of a type which may be set to cause the phonograph to reproduce in sequence a plurality of sound recordings.

The solid rectangle 41 enclosed by the dashed lines 8 in Fig. 8 represents all of the mechanism embodied in such a coin actuated phonograph which does not need to be altered or changed in order to convert such phonograph for use with the system of my invention.

Such of the phonograph mechanism 8 as plays an active part in the control functions of the system of my invention has, however, been illustrated diagrammatically in Fig. 8. This mechanism includes an electric motor 42 adapted to drive a turn table 43 upon which the various phonograph records are placed in sequence so as to permit the reproduction by the sound reproducer 38 of the material recorded on such phonograph records. The sound reproducer 38 is mechanically connected as by means of a suitable linkage 44 to a latch member 45 adapted to hold master relay contacts MR-1 in a closed position after energization of a master relay coil MR until such time as the sound reproducer 38 has been moved toward the center of the phonograph record a distance sufficient to represent the reproduction of all of the material recorded on such phonograph record.

One terminal of the master relay MR is ordinarily connected as by means of a conductor 46 to a terminal 47 included in the equipment represented by the rectangle 41 (this connection is left undisturbed), while the other terminal of the master relay MR is connected as by means of a conductor 41a to a coin switch 48, the coin switch 48 being in turn connected as by means of a conductor 49 to a terminal 50 included in the apparatus represented by the rectangle 41. The conductor 41a is disconnected from the coin

switch 48 and instead connected to a terminal 51 provided in the adapter unit 7. Similarly, the conductor 49 is disconnected from the coin switch 48 and extended into connection with another terminal 52 provided in the adapter unit 7. The wires 53 and 54 which are connected respectively to the contact members forming the relay contacts MR-1 are disconnected and extended into connection with electrical terminals 55 and 56 provided in the adapter unit 7.

The electrical supply cable 10b which ordinarily supplies power to the coin actuated phonograph 8 includes conductors 57 and 58 which are ordinarily respectively connected to terminals 47 and 59 included within the rectangle 41. The conductor 58 is ordinarily also connected to a terminal 60 so that certain power equipment, notably the turn table motor 42, may be connected to the terminals 59 and 60 and controlled independently of the master relay MR which is connected to terminals 47 and 50. The conductor 58 is disconnected from the terminal 60 and instead extended into connection with a terminal 61 provided on the adapter unit 7 and another terminal 62 provided on the adapter unit is connected as by means of a conductor 63 to the aforementioned terminal 60.

The above described alterations are all that is necessary to adapt the phonograph 8 to independent control from each of the coin collecting stations 1-4. However, in order that the sound producing devices 19 incorporated in such stations may operate to reproduce the material which is reproduced by the sound reproducer 38, it is necessary to also extend the sound circuit of the phonograph 8 into the adapter unit 7. The loud speaker 40 of the phonograph is ordinarily connected as by means of conductors 64 and 65 to amplifier output terminals 66 and 67, respectively. The conductors 64 and 65 are each disconnected from the loud speaker 40 and extended into connection with terminals 68 and 69 provided on the adapter unit 7.

Power for operating the system is obtained by means of the electrical supply cable 10a which includes conductors 70 and 71 connected respectively to a power transformer PT, secondary terminals 72 and 73 of which serve as a source of supply of low voltage power for the operation of the system. It is recognized that electrical power at substantially any voltage may be used for operating the system of my invention, but in the interest of safety and economy, it is preferred to use a low voltage source.

The manner in which the various instrumentalities are interconnected and cooperate with each other to achieve the desired results can perhaps best be described by assuming certain conditions of operation and describing the various electrical connections employed as the description of the operation of the system is carried forward. Assume, for example, that a patron deposits a coin in coin collecting station 1 as by inserting a suitable coin in the coin receiving aperture 17. The coin falls by gravity down the coin chute 15 until it engages the coin engaging projection 32 (see Fig. 4). When the coin arrives in this position it engages the arm 26 and closes the contacts of the switch CS-1, 70 being the coin switch CS-1 associated with the coin collecting station 1.

One side of the coin switch CS-1 is supplied with power from the transformer PT as by means of a conductor 74 which is connected to the secondary terminal 72 and enclosed within

the cable 6. The conductor 74 extends into connection with all of the coin collecting stations 1-4 and may be connected to one terminal of the coin switch ICS-1 as by means of a conductor 75. The other terminal of the coin switch ICS-1 is connected as by means of conductors 76 and 77 to one terminal of a coil of the coin relay ICR, the other terminal of such relay coil being connected as by means of a conductor 78 to a conductor 79 which is included in the cable 6.

The conductor 79 is extended to one terminal of a normally closed contact IR-1 of the impulse relay IR, the other terminal of the contact IR-1 being connected as by means of a conductor 80 to the other low voltage terminal 73 of the transformer PT.

It will be seen, therefore, that the closing of the coin switch ICS-1 by the insertion of a coin into the coin collecting station 1 serves to complete an electric circuit including the coil of the relay ICR. The resulting energization of the relay ICR serves to close its various normally open contacts ICR-1, ICR-2, ICR-3 and to also open its normally closed contact ICR-4.

One terminal of the normally open contact ICR is connected as by means of a conductor 81 to the aforementioned power supply conductor 74 and the other terminal of the contact ICR-1 is connected as by means of a conductor 82 to the aforementioned conductor 77. This connects the contact ICR-1 in parallel with the coin switch contacts ICS-1 so that immediately upon energization of the coin relay ICR a self-holding circuit is established through conductors 81 and 82, permitting the re-opening of the coin switch contacts ICS-1 to occur without causing de-energization of the coil of the relay ICR.

The energization of the relay coil ICR serves to move its armature 28 from a position such as that illustrated in Fig. 4 to a position such as that illustrated in Fig. 5. This movement of the armature serves to change the positions of the escapement members 30 and 31 and so permit the coin to again move downwardly through the coin chute 15 until such downward movement is arrested by the center coin engaging projection 33.

The closing of the relay contacts ICR-2 serve to place the phonograph 8 in operation. The circuits associated with the contacts ICR-2 include a conductor 83 which is connected as by means of conductors 84 and 80 to the low voltage terminal 73 of the power transformer PT. The conductor 83 is one of the group of conductors included in the cable 6 and extends into connection with all of the coin collecting stations 1-4. Thus, by means of conductors 74 and 83 the low voltage power supply derived from the power transformer PT is transmitted to each of the coin collecting stations 1-4, permitting the connection of the lamps 22 between these conductors as by means of a series circuit 84a.

One terminal of the relay contact ICR-2 is connected as by means of a conductor 85 to the conductor 83 and the other of such relay contacts is connected as by means of a conductor 86 to the conductor 87 which is also one of the conductors included in the cable 6. The conductor 87 is extended into the adapter unit 7 and there is connected as by means of a conductor 88 to one terminal of a small electric motor IR-M forming a part of the impulse relay IR. The other terminal of the motor IR-M is connected as by means of a conductor 89 to one terminal of a normally closed relay contact CR-1, the other terminal of such contact being connected as by

means of a conductor 90 to the aforementioned power supply conductor 74. Thus, the closing of the coin relay contacts ICR-2 serves to complete an electric circuit through the impulse relay motor IR-M. This motor is connected by means of suitable reduction gearing and shafting, indicated generally by reference character 91, to a switch control disk 92 in such manner as to, upon energization, rotate the disk 92 in a direction such as that indicated by arrow 93 in Fig. 7. The speed of the motor and the drive ratio of the mechanical connection 91 is preferably so arranged as to drive the disk 92 at a rotational speed lying within the range of from four to fifteen revolutions per minute.

The disk 92 is preferably provided with a projection 94 to which may be attached a return spring 95 acting to return the disk 92 to a position such as that illustrated in Fig. 7 upon deenergization of the motor IR-M. The motor IR-M is preferably mounted on a suitable supporting bracket 96 which in turn provides a support for a switch structure 97. The switch structure 97 includes a supporting bracket 98 upon which is pivotally secured a switch actuating arm 99. The arm 99 is preferably pivotally secured to the bracket 98 for pivotal movement about an axis disposed parallel to the axis of rotation of the disk 92 and the arm 99 includes a downwardly extending portion 100 terminating in a roller 101 which is disposed in a position to be engaged by the projection 94 upon a partial rotation of the disk 92.

The arm 99 also includes an upwardly and rearwardly extending portion 102 terminating in a roller 103 engaged with a central spring leaf 104 which is common to two relay contacts; viz., normally closed relay contact IR-1 and normally open contact IR-2, the other contact members of these relay contacts comprising contact springs 105 and 106, respectively. These springs are so adjusted that upon engagement of the projection 94 with the lower roller 101, pivotal movement of the arm 99 from the position represented by solid lines in Fig. 7 to the positions represented by dotted lines in that figure serves to move the contact spring 104 through a distance sufficient to complete an electric circuit between the contact springs 104 and 106 and a short time later to open the electric circuit between the contact springs 104 and 105.

The impulse relay IR preferably includes also, another pair of contact springs 107 and 108 which are supported by the switch supporting structure 97. These contact springs are normally disposed in positions such that there is no electric circuit established between them. The upper contact spring 107 is, however, extended to a position such that additional rotation of the disk 92 (beyond a position engaging the projection 94 with the contact engaging arm roller 101) will bring the projection 94 into engagement with the spring 107 sufficiently to complete an electrical circuit between the spring 107 and the spring 108.

It will thus be seen that the energization of the motor first causes the closing of the impulse relay contacts IR-2 which are connected between aforementioned conductors 80 and 87, thus serving to maintain the circuit to the impulse relay motor IR-M, even though the coin relay contacts ICR-2 should be subsequently opened.

A short time after the closing of the relay contacts IR-2, the relay contacts IR-1 are opened, thus breaking the circuit between conductors 79

and 80 and thus de-energizing the coin relay 1CR. De-energization of the coin relay allows the armature 28 thereof to return to its initial position to place the coin escapement members 30 and 31 in a position such as that illustrated in Fig. 6. This allows the coin to again resume its downward travel in the coin chute 15 until it engages the lowermost coin engaging projection 36. Engagement of the coin with the projection 36 is accompanied by the closing of the second coin switch 1CS-2.

This coin switch is connected by means of conductors 109 and 110 in parallel with the upper coin switch 1CS-1 so that the closing of the lower coin switch 1CS-2 serves to prepare a circuit through the coin relay 1CR identical to the actuating circuit therefor first described. This circuit is, however, interrupted by the now open normally closed impulse relay contacts IR-1. By having reference to Fig. 7, it will be observed that continued rotation of the disk 92 in the direction of the arrow 93 after engagement of the projection 94 with the roller 101 will serve to cause the projection to pass completely under the roller and remove the pressure which is applied by the switch actuating arm 99 to the center contact spring 104, thus allowing this spring to restore to its initial condition, closing the impulse relay contacts IR-1 and re-opening the relay contacts IR-2.

Re-closing of the normally closed contacts IR-1 serves to complete the circuit to the coin relay 1CR. The resultant energization of that relay results in the shifting of the positions of the coin escapement members 30 and 31 from the position which is illustrated in Fig. 6 to a position such as that illustrated in Fig. 5, thus releasing the coin in the coin chute 15 and allowing that coin to drop into the coin box at the bottom of the housing 16. The resultant immediate re-opening of the coin switch 1CS-2 does not, however, de-energize the coin relay 1CR for the reason that a supply circuit therefor is established through conductors 81 and 82 and the coin relay contacts 1CR-1.

Mention has been made hereinbefore of the fact that the impulse relay contacts IR-1 and IR-2 overlap, that is to say, that for a brief period during the movement of the center spring 104 between its two positions that both of these contacts are closed. Attention is directed to the fact that this overlap serves to maintain the motor IR-M energized during the last described phase of the operation, power to the motor IR-M being supplied first through the contacts IR-2 and then upon closing of the contacts IR-1 through the circuit which is extended through the coin relay contacts 1CR-2 which is completed immediately upon the closing of the impulse relay contacts IR-1.

It will thus be seen that the disk 92 continues in its rotation and that such continued rotation will serve to bring the projection 94 into engagement with the contact spring 107 after a brief interval and thereby close normally open impulse relay contacts IR-3. These contacts are connected to the aforementioned terminals 51 and 52 which, it will be recalled, are connected in the control circuit for the phonograph master relay MR. The resultant energization of the relay MR by means of power supplied from the phonograph terminal 47 through conductor 46 to the coil of the relay MR and from thence through conductor 47 to terminal 51, relay contact IR-3, conductor 49 to terminal 52, and conductor 48 to the other power

supply phonograph terminal 50 results in the closing of the master relay contacts MR-1 and their being immediately held in such closed position by the mechanical latch 45.

Closing of the relay contacts MR-1 serves to complete a circuit between the adapter unit terminals 55 and 56 to which they are connected by means of conductors 53 and 54. The terminal 55 is connected as by means of a conductor 111 to the low voltage terminal 73 of the transformer PT and the terminal 56 is connected by means of a conductor 112 to one terminal of the coil of the operating relay OR, the other terminal of such coil being connected as by means of a conductor 113 to the aforementioned power supply conductor 74. The resultant energization of the relay OR serves to open its normally open contacts OR-1 to thereby de-energize the motor IR-M of the impulse relay IR, with the subsequent result that the control disk 92 thereof is restored to its initial or rest position by the spring 95.

The energization of the relay OR also serves to close normally open contacts OR-3 thereof which are connected by means of conductors 114 and 115 to the aforementioned adapter unit terminals 61 and 62. These terminals, it will be recalled, are connected in series between the supply conductor 58 and the supply terminal 80 of the phonograph so that energization of the relay OR serves to complete a power supply circuit to certain of the power equipment included in the phonograph 8, notably the turn table motor 42 and the record selection and transfer equipment. Closing of the relay contacts OR-3 thus serves to place the turn table motor 42 in operation and start the reproduction of a phonograph record. The relay OR is also provided with normally open contacts OR-2 which are connected between the conductors 79 and 80 and which serve to maintain the coin relay 1CR energized irrespective of the operation of the impulse relay IR.

The circuits for supplying the sound signals to the sound producing devices 19 provided in each of the coin collecting stations 1-4 include a pair of conductors 116 and 117 which are extended respectively from the adapter-unit terminals 68 and 69 to primary terminals of a matching transformer MT. The primary winding of this transformer is preferably provided with a plurality of taps so that the conductors 116 and 117 may be connected to the transformer MT in such manner that the primary winding included between these conductors accurately matches the output impedance of the amplifier provided in the phonograph 8. The secondary of this matching transformer is likewise provided with a plurality of taps permitting connection thereto of a pair of conductors 118 and 119 in such manner as to include between those conductors an amount of secondary winding such that the impedance thereof will accurately match the combined impedance of all of the loud speakers when such speakers are connected in parallel.

The conductor 118 is extended into connection with the aforementioned cable conductor 83 so that this conductor may serve as a common for both the control currents and the sound signals. Stability may be insured by grounding the conductor 83 as by a ground conductor 120. The conductor 119 is extended through the cable 6 and into connection with all of the coin collecting stations 1-4. In each of the coin collecting stations the conductor 119 is connected by means of a conductor 121 to a normally closed coin re-

lay contact 1CR-4, the other terminal of which is connected as by means of a conductor 122 to a resistance 1R, the other terminal of the resistance being connected as by means of a conductor 123 to the grounded conductor 83. The conductor 121 which is tapped off of the cable conductor 119 is also connected to a normally open coin relay contact 1CR-3, the other side of such contact being connected as by means of a conductor 124 to one terminal of a primary winding of a loud speaker transformer ST, the other primary terminal of such transformer being connected as by means of a conductor 125 to the grounded conductor 83.

It will be readily observed that when the coin relay 1CR is de-energized, normally closed contacts 1CR-4 thereof serve to connect the resistor 1R between the conductors 83 and 119 and that upon energization of the coin relay 1CR, contact 1CR-3 thereof serves to connect the primary winding of the speaker transformer ST between the conductors 83 and 119. Thus, the impedance of the circuits connected between conductors 119 and 83 may be caused to remain constant irrespective of the energized or de-energized condition of the coin relay 1CR by adjusting the resistance of the resistor 1R to match the impedance of the transformer ST. The secondary winding of the transformer ST is connected as by means of conductors 126 and 127 to the loud speaker 19.

It will be apparent from the foregoing that as soon as the phonograph 8 is placed in operation, alternating current corresponding to the material recorded on a phonograph record will be impressed between conductors 119 and 83 and that as soon as the coin relay 1CR is energized, the speaker 19 will be alternatively connected between these conductors so that the material recorded on the phonograph record and reproduced by the phonographic reproducer 38 will in turn be reproduced as sound by the speaker 19. As soon as the playing of the phonograph record is finished the inward movement of the reproducer 38 will, by virtue of the mechanical link 44, disengage the latch 45 from the master relay contact MR-1 and allow that contact to open. The opening of contacts MR-1 in turn de-energizes the operating relay OR and this in turn interrupts the circuits supplying power to the turn table motor 42.

It will be noted that control relay 1CR is maintained energized from conductors 74 and 83 through the following circuit: 81, 1CR-1, 82, 1CR, 78, 79, IR-1, 80. Thus, immediately upon the re-closing of the operating relay contacts OR-1, the impulse relay motor IR-M is re-energized so as to momentarily open the impulse relay contacts IR-1. Opening of these contacts in turn de-energizes the coin relay 1CR and the de-energization of that relay in turn opens the circuit supplying power to the impulse relay motor IR-M, allowing the spring to return the impulse relay to its normal or off position. Thus, at the completion of the playing of the phonograph record, the equipment is left in the same condition as it was at the time the operation was initiated by the insertion of a coin into the coin chute 15.

The system above described operates to insure that a person depositing a coin in one of the coin collecting stations 1-4 will receive at least a full recording and that should such person deposit a coin during the time a phonograph record is being reproduced at a different coin collecting station, the remainder of the selection then play-

ing will be reproduced at the station in which the coin was last inserted and then the equipment will be again re-operated to reproduce at such last station one complete phonograph recording.

- 5 Suppose, for example, that the equipment was placed in operation initially by the insertion of a coin in the coin chute of coin collecting station 2. As the recording is being reproduced the coin relay 2CR of the coin collecting station 2 will be energized, the coin will be collected and the operating relay OR in the adapter unit 7 will be energized. With the various instrumentalities in such condition, assume that a coin is placed in the coin chute 15 of coin collecting station 1. 15 Arrival of the coin at the position illustrated in Fig. 4 closes coin switch 1CS-1 and thereby energizes the coin relay 1CR which in turn operates the escapement mechanism to move the coin to the position illustrated in Fig. 5. This closing of 20 the relay 1CR operates the contacts 1CR-3 and 1CR-4 thereof to connect the loud speaker 19 to the conductors 119 and 83 to thereby reproduce at the coin collecting station 1 the selection which was up to that time being played for the benefit 25 of the patron at coin collecting station 2. The energization of coin relay 1CR does not, however, serve to operate the impulse relay IR for the reason that the circuit to the motor IR-M thereof is opened at operating relay contact OR-1. As soon, however, as the selection being played 30 by the phonograph 8 is completed, the resultant opening of the master relay contact MR-1 de-energizes the operating relay OR so as to close its contacts OR-1 and thereby complete the circuit 35 through the impulse relay motor IR-M. As soon as this circuit is completed, the impulse relay operates to open and close its contacts IR-1 and IR-2 and thereby de-energize both of the coin relays 1CR and 2CR. The coin relay 1CR is, however, immediately re-energized by the movement 40 of the coin in the coin chute 15 from the position illustrated in Fig. 5 to that illustrated in Fig. 6 to close the second coin switch 1CS-2. Closure of the second coin switch 1CS-2 again 45 re-energizes the relay 1CR so as to effect the collection of the coin and to maintain the circuit to the impulse relay motor IR-M completed, thereby causing the impulse relay IR to close its contacts IR-3. As previously described, closing of 50 the contacts IR-3 places the phonograph 8 in operation to reproduce another phonographic recording.

In a similar manner, the mechanism above described functions to permit the insertion of two or more coins in the coin chute 15 and assures that one complete phonograph record will be reproduced for each of the coins so inserted. Assume, for example, that a coin 35 is inserted and slides down the chute 15 to a point engaging 55 the coin engaging projection 32 in the manner illustrated in Fig. 4. Suppose also that coins 35a and 35b represented in Fig. 4 by dotted lines, are also placed in the coin chute. Closing of the coin switch 1CS-1 by the coin 35 will serve to 60 energize the relay 1CR and shift the positions of the escapement mechanism to that which is illustrated in Fig. 5. As soon as the impulse relay IR is actuated in response to the energization of the relay 1CR, the relay 1CR will be de-energized and the escapement mechanism will be shifted to the position illustrated in Fig. 6. Note that in this figure both of the coins 35a and 65 35b are caught and held in the uppermost position by the upper coin engaging projection 32. This is accomplished by proper adjustment of

the spacing between the projections 32 and 33 and proper clearance between the under sides of these projections and the bottom of the coin chute 15.

As soon as the impulse relay IR continues its operation sufficiently to re-energize the coin relay ICR, the escapement parts will again be shifted to the position which is illustrated in Fig. 5, effecting a collection of the coin 35 and shifting the coin 35a to the position which is occupied by the coin 35 in Fig. 5. The equipment at this point functions to reproduce a complete recording in the manner above described and as soon as such recording is completed, the resultant de-energization of the operating relay OR will again re-energize the impulse relay motor IR-M. The resultant opening of contacts IR-2 will de-energize the relay ICR and serve to move the coin 35a from a position such as that occupied by coin 35 in Fig. 5 to a position such as that occupied by coin 35 in Fig. 6. This closes the second coin switch 2CS so as to immediately re-energize the relay ICR and effect a collection of the coin and at the same time re-establish the circuit through the impulse relay motor IR-M and insure its continued operation to a point placing the phonograph 8 in operation. Thus, it will be seen that the mechanisms function to collect one coin for each phonograph record which is reproduced at the station into which the coins are inserted irrespective of the number of coins which are placed in the coin chute.

From the foregoing it will be observed that the assurance that a customer will receive full value for the coin which he deposits in the coin chute is achieved by means of the escapement mechanism and the coin switches associated therewith which serve to hold the coins and prevent collection thereof until the apparatus is in a condition to deliver full measure of commodity or service paid for.

In this connection, attention is directed particularly to the fact that the escapement mechanisms and the coin relays CR operate to hold a coin in a position such that the contacts of the coin switch are closed and that the release of the coin for further travel along the coin chute occurs only at such times as the various functions intended to be initiated by the closing of the coin switch contacts are actually started. Thus, it is insured that each of the coin switches will be closed for a sufficient length of time to permit the function directly resulting from the closing of such switch to be completed, and prevents the closing and reopening of the coin switch from occurring with such great rapidity as to fail to properly operate the various instrumentalities controlled thereby.

It will also be noted by having reference to Figs. 4 and 6 that the operating arms 24 of the coin switches are preferably disposed in such positions relative to the upper and lower coin engaging escapement projections 32 and 36 as to engage a coin held by these projections at a point disposed above the center of the coin. This prevents the restoring force which is applied to the arms 24 from impeding the movement of the coin upon release of the escapement mechanism and actually provides a small starting force tending to prevent inadvertent sticking of the coin in the coin chute.

While I have, in the foregoing, described the coin collecting stations as being employed in a sound reproducing system, it will be apparent

to those skilled in the art that the same principles and details of construction may be readily adapted for use with any type of coin actuated mechanism and that when so adapted the devices will permit the insertion of two or more coins in each of the coin collecting stations and will also permit the use of two or more stations with a single coin actuated device and will at the same time insure that patrons receive full measure for each coin they have inserted in the mechanism.

While I have shown and described the preferred embodiment of my invention, I do not desire to be limited to any of the details of construction shown or described herein, except as defined in the appended claims.

I claim:

1. In a coin operated control device, the combination of: means defining a coin channel for simultaneously receiving a plurality of coins; a coin receiver disposed at a discharge end of said channel; a coin feeding mechanism in said channel normally defining a zone and actuatable to advance the lowermost one of said coins into said zone while holding the remainder of said coins above said zone; means in said channel above said feeding mechanism operable upon engagement by said lowermost one of said coins to actuate said feeding mechanism; and means operable subsequently to again actuate said feeding mechanism to thereby advance said lowermost coin into said receiver and advance the next one of said coins into said zone.

2. In a coin operated control device, the combination of: means defining a coin receiving channel communicating with a coin receiver; a coin feeding mechanism in said channel movable from a first position defining an isolated zone in said channel to a second position dividing said channel into an upper and a lower portion each including a part of said zone; means in said channel operable upon engagement by a coin to move said feeding mechanism from said first to said second position to permit said coin to advance into said zone, whereby subsequent movement of said feeding mechanism back to said first position will confine said coin in said zone; and means responsive to confinement of said coin in said zone for again moving said feeding mechanism to said second position, whereby said coin is permitted to advance into said coin receiver.

3. In combination with a coin controlled device including means responsive to the closing of an electric circuit for initiating a predetermined operation and having means responsive to initiation of said operation for creating an electrical impulse; means defining a coin receiving channel communicating with a coin receiver; a coin feeding mechanism in said channel actuatable to advance a coin in said channel a predetermined distance through said channel; means responsive to the insertion of a coin in said channel for actuating said feeding mechanism; means responsive to actuation of said feeding mechanism for closing said electric circuit; and means responsive to the creation of said electrical impulse for again actuating said feeding mechanism to thereby advance said coin to said coin receiver.

4. In combination with a coin controlled device including means responsive to the closing of an electric circuit for initiating a predetermined operation and having means responsive to the initiation of said operation for creating an electrical impulse; means defining a coin receiving channel communicating with a coin receiver;

coin feeding mechanism in said channel actuatable to advance a coin in said channel a predetermined distance through said channel; electric switch means in said channel closable through engagement of a coin therewith; an electromagnetic means coupled to said switch means and responsive to closing thereof for actuating said feeding mechanism; and means on said electromagnetic means for closing said electric circuit, said electromagnetic means being also responsive to the creation of said electrical impulse for again actuating said feeding mechanism to thereby advance said coin to said coin receiver.

5. In combination with a coin controlled device including means responsive to the closing of an electric circuit for initiating a predetermined operation and having means responsive to the initiation of said operation for creating an electrical impulse; means defining a coin channel for simultaneously receiving a plurality

of coins; a coin receiver disposed at a discharge end of said channel; a coin feeding mechanism in said channel normally defining a zone and actuatable to advance the lowermost one of said 5 coins into said zone while holding the remainder of said coins above said zone; electric switch means in said channel above said feeding mechanism closable upon engagement by said lowermost one of said coins therewith; electromagnetic means coupled to said switch means and responsive to closing thereof for actuating said feeding mechanism; and means on said electromagnetic means for closing said electric circuit, said electromagnetic means being also responsive to the creation of said electrical impulse for again actuating said feeding mechanism to thereby advance said lowermost coin into said coin receiver and advance the next one of said coins into said zone.

10 15 20 WILLIAM S. FARRELL.
